CHANGE PURSE CONSTRUCTION

Frank G. Dobbs and Stephan H. Dobbs,
New York, N. Y.

Application October 27, 1953, Serial No. 388,576

5 Claims. (Cl. 150—37)

1

The invention relates to receptacles, and relates more particularly to receptacles of the purse type that receive currency in the form of bills and coins.

In purses of this type, it has always been a major source of annoyance that it needed to be opened to take out money, and had also needed to be opened for the insertion of money, such as the return of the change.

It is among the objects of the invention to provide for means that will make it unnecessary to open the purse for the insertion of money.

Generally speaking, this is accomplished by providing a slot in the front wall of the purse at some distance from the usual open end through which customarily the money is passed, through which coins and bills may be pushed into the pocket without uncovering the aforesaid open end.

Although the invention will be explained in the following in connection with the simplest form of purse, it will be understood that it may be applied to pocketbooks and other receptacles, such as wallets and billfolds and generally to all kinds of purses, and that this simplification is made only for the purpose of illustration and that no limitation is intended thereby save as set out in the claims hereof.

The foregoing and other objects of the invention will be best understood from the following description of and exemplifications thereof, reference being had to the accompanying drawings, wherein:

Fig. 1 is a perspective view of a purse in accordance with one embodiment of the invention;

Fig. 2 is a front elevational view thereof;

Fig. 3 is a sectional view taken on line 3—3 of Fig. 2;

Fig. 4 is a sectional view similar to Fig. 3, but showing the step of inserting a coin;

Fig. 5 is a front elevational view similar to Fig. 2, but embodying a modification;

Fig. 6 is a sectional view taken on line 6—6 of Fig. 5;

Fig. 7 is a front elevational view similar to Figs. 2 and 5, but embodying a further modification; and

Fig. 8 is a sectional view taken on line 8—8 of Fig. 7.

In carrying the invention into effect in one of the embodiments which have been selected for illustration in the accompanying drawings and for description in this specification, and referring now particularly to Figs. 1—3, there is provided a purse generally indicated at 10. The purse 10 comprises a body 11 that in this exemplification

2

consists of a rear wall 12 and a front wall 13 that define therebetween a pocket 14. The pocket 14 is open at the top 16. A cover flap 15 is connected to, for instance integrally with, the rear wall 12, and is movable between a closed and an open position. In the closed position, which is shown in Fig. 3, the flap 15 covers the open top 16 thereby closing the pocket 14. A partially open position is shown in Fig. 1, and the flap 15 may be opened further until it is aligned with the rear wall 12 for affording access to the interior of the pocket 14 (not shown in detail).

Fastening means, such as a two-part snap fastener 17, is provided between the front wall 13 and the flap 15 for removably fastening the flap 15 to the front wall 13 in the closed position.

Below the open top 16, there is provided in the front wall 13 an opening or slot 18 that is elongated horizontally and narrow in the vertical direction and which is dimensioned for the passage of customary coins, for instance in United States currency for up to one-half dollar piece, or even larger, as well as for the passage of folded currency bills.

The slot 18 forms an intercommunication between the interior of the pocket 14 and the exterior of the body 11, and thus provides a passage for coins to be pushed therethrough into the pocket 14. The slot 18 has an upper lip 19 and a lower lip 20. At least one of these lips 19 and 20 is resiliently flexible, or the material of the front wall 13 may be resiliently flexible, while the remainder of the purse 10 may be flexible or semi-rigid or rigid.

In the embodiment of Figs. 1—3, a reinforcement 21 is provided to reinforce at least the major portion of the lower lip 20. This reinforcement comprises a channel member of which the front portion 22 provides an embellishment for the lower lip while reinforcing it, and the rear portion 23 of the channel 21 lies flat against the interior area adjacent the lower lip 20. The channel 21 may be clamped over the lower lip 20, and may consist of metal and the front portion 22 may be polished to afford a pleasing impression upon the eye.

In the flap 15 there is formed an aperture 24 that, in the closed position of the flap 15 is in registry with the slot 18 exposing the slot 18 as well as reinforcement channel 21 to the eye of the observer. In the closed position, the aperture provides a sort of frame for the design of the slot 18 and channel 21, while the remainder of the flap 15 overlaps a portion of the front wall 13.

As best shown in Fig. 4, the upper lip 19 is

flexible, and it is resilient, and may be pressed inwardly by a coin that is pushed into the pocket 14. After the coin is in, the upper lip 19 will snap back into its original position shown in Fig. 3 and thereby there is prevented an accidental removal of a coin from the interior of the pocket 14 through the slot 18.

In using the purse, money is removed by opening the flap 15 to gain access to the interior of the pocket 14. Thereafter, the purse may be closed, by removably securing the flap 15 to the front wall 13 by means of snap fastener 17. Money may thereafter be inserted into the pocket 14 through the slot 18, for instance in the manner shown in Fig. 4. Naturally, if desired, money may also be inserted by first opening the flap 15 and passing it through the open top 16.

In the modification shown in Figs. 5 and 6, the slot 118 provides for a gap between the upper lip 119 and the lower lip 120. The upper and lower lips thus never touch, and the slot 118 is always open for the gap.

A reinforcement such as an eyelet 26 is connected to the front wall 13 throughout the contour or edge of the slot 118. The eyelet 25 is elongated and provides between its parallel arms 27 and 28 a gap 25 which is sufficiently wide (in the vertical direction) to pass coins that are forced through though sufficiently narrow to make it difficult for coins to pass through it accidentally upwardly from the pocket 14. As an example, the gap 118 may be $1\frac{1}{4}$ " long and $\frac{3}{8}$ " wide.

The aperture 24 of the flap 15 again is in registry with the slot 118, and also with the reinforcement eyelet 26, when the flap 15 is closed, providing a frame for the eyelet 26 and the slot 118. The eyelet 26 may be made of metal, and have a polished finish providing a pleasing design pattern within the frame of the aperture 24. In this modification, the tops 119 and 120 need not be flexible, though they may.

In the modification shown in Figs. 7 and 8, the lips 19 and 20 of the slot 18 are without reinforcement and flexible.

It will be apparent to those skilled in the art that the novel principles of the invention disclosed herein in connection with specific exemplifications thereof will suggest various other modifications and applications of the same.

It is accordingly desired that in construing the breadth of the appended claims they shall not be limited to the specific exemplifications of the invention described herein.

Having thus described the invention, what we claim as new and desire to be secured by Letters Patent, is as follows:

1. In a purse structure, in combination, a body defining a pocket open on top and including a wall, a cover for said open top secured to the body and being movable between a closed position wherein it overlaps a portion of said wall and covers said open top and, respectively, an open position wherein it uncovers said portion and said open top, said portion of said wall having a slot forming an intercommunication between said pocket and the exterior of said body, said cover having an aperture positioned for registry with said slot when said cover is in the closed position, said slot and aperture being dimensioned sufficiently large for the passage of coins.

2. In a purse structure as claimed in claim 1, said slot being lined by two lips integral with said wall, at least one of said lips being sufficiently resilient for yielding upon insertion of a coin to form with said other lip a coin passage and to return thereafter to a position adjacent said other lip.

3. In a purse structure as claimed in claim 1, said slot being lined by two lips integral with said wall, and reinforcement means secured to said wall adjacent said slot and being operable for reinforcing at least one of said lips.

4. In a purse structure, a body having a front and rear wall defining a pocket open on top, and a flap connected to said body and normally positioned to cover said open top and at least a portion of said front wall, said portion of said front wall being provided with an opening communicating with the interior of said pocket and the exterior of said body, said flap being formed with an aperture being in the normal position of said flap in registry with said opening, said opening and said aperture being dimensioned for the passage of coins, and a frame connected to said front wall and surrounding said opening throughout the contour thereof.

5. In a purse structure, as claimed in claim 4, said aperture having a larger area than the orbit of said frame to expose the latter in said normal position.
